UNITED STATES PATENT OFFICE.

MARTIN GRATZ, OF BUTTE, AND GEORGE W. SHAW, OF HELENA,
MONTANA.

WHEEL.

SPECIFICATION forming part of Letters Patent No. 627,998, dated July 4, 1899.

Application filed October 29, 1898. Serial No. 694,948. (No model.)

To all whom it may concern:

Be it known that we, MARTIN GRATZ, of Butte, in the county of Silver Bow, and GEORGE W. SHAW, of Helena, in the county 5 of Lewis and Clarke, in the State of Montana, citizens of the United States, have invented new and useful Improvements in Wheels, of which the following is a specification.

Our invention relates to vehicle-wheels, and 10 contemplates the provision of a strong and durable wheel which is so constructed as to admit of its spokes being quickly and easily tightened when the same become loose.

With the foregoing in view the invention 15 will be fully understood from the following description and claims when taken in conjunction with the annexed drawings, in which—

Figure 1 is a broken diametrical section of a wheel constructed in accordance with our 20 invention. Fig. 2 comprises disconnected detail views of the several parts entering into the wheel. Fig. 3 is a broken diametrical section of a modified construction of wheel.

In the said drawings similar letters designate corresponding parts in all of the several 25 views, referring to which—

A is the felly of the wheel. B is the hub-body, and C are the spokes, the latter being by preference slightly dished, as shown.

30 The felly A is provided at suitable intervals with the sockets a for the outer reduced ends of the spokes, which sockets have flanges b arranged to bear against the inner side of the felly and wings c disposed at opposite 35 sides of the felly, as shown, so as to strengthen the connection of the spokes thereto.

The hub-body B, as best shown in Fig. 3, contains a suitable boxing c' and is provided with an outwardly-extending sleeve d, radially-disposed sockets e, and an annular recess f, which intersects the inner ends of the sockets e and has its outer wall tapered, for a purpose presently to be described. The said body B is also provided, as best shown in 45 Figs. 1 and 2, with an inner peripheral flange f', the inner side of which forms a continuation of the inner side wall of the several spoke-sockets, for a purpose presently pointed out. In the sockets e of the hub-body metallic ferrules D are snugly fitted after the manner shown in Fig. 1. These ferrules D have their

inner end walls g inclined and are designed to receive the inner reduced portions h of the spokes C, which have their inner ends i beveled in conformity to the inclined walls g of 55 the ferrules, so as to entirely occupy the same.

E is a movable spoke spreader and tightener, in the form of a taper-sleeve, which is arranged upon the sleeve d of the hub-body and rests within the annular recess f of said 60 body and in engagement with the inclined end walls of the ferrules D, as illustrated in Fig. 1. This taper-sleeve E is provided at suitable intervals with transverse apertures j and is adjustably connected with the hub- 65 body through the medium of headed bolts F, which take through the apertures j of the sleeve and into threaded sockets k in the inner wall of the said body. By virtue of this

construction all of the spokes, when they are 70 rendered loose by any cause, may be quickly and easily tightened by simply turning the bolts F so as to move the taper-sleeve E inwardly. When the sleeve E is thus moved inwardly, it will move the ferrules D, and 75 consequently the spokes C, outwardly in a radial direction and will bind the spokes against the felly, thus rendering the wheel stiff and rigid.

G is an outer shell which surrounds the extended sleeve d of the hub-body and serves to close the outer side of said body. This shell G receives within it, but does not engage, the outer wall f² of the spoke-sockets of the body B, and is provided with a flange 80 f³, which surrounds the said outer wall f² of the spoke-sockets, as illustrated. Said shell G is detachably connected with the body B by metallic screws l, which take through apertures in the shell-flange f³ and into threaded apertures in the flange f' of the body B and are arranged between the spokes, as shown. It is obvious that when desired bolts with nuts may be substituted for the screws l, in which event the apertures in the flange 95 f' of the body need not be threaded.

As will be readily observed, the outer shell G slips freely over the sleeve d of the body and does not engage any other part of the body, but presses directly by its flange f³ 100 against the spokes. Consequently when the flange of the shell is bolted to the flange f'

of body B the spokes will be firmly clamped between the flanges f' f^3 , which in practice are about one and one-half inches wide, and a stiff and rigid wheel insured.

5 In Fig. 3 of the drawings we have illustrated a modified construction of wheel which is similar to that shown in Figs. 1 and 2, with the exception that the outer wall f^4 of the spoke-sockets e' is of the same diameter as the inner flange f' , and the flange f^5 of the outer shell G' bears against the outside of the said wall f^4 . This modified construction also differs from that shown in Figs. 1 and 2 in that the screws or bolts l' take through the outer 15 spoke-socket wall f^4 as well as through the flange f^5 of the shell G'.

By reason of the construction disclosed in Figs. 1 and 2 the spokes may be better clamped and held in the hub, and we therefore prefer 20 such construction to that illustrated in Fig. 3.

It will be appreciated from the foregoing that we have provided a wheel which is exceedingly strong and durable both as regards the connection of the spokes with the felly 25 and their connection with the hub. It will also be observed that all of the spokes may be quickly and easily tightened and the wheel rendered stiff and rigid when necessary by the adjustment of a single element—viz., the 30 taper sleeve—and this without wearing or breaking down the inner ends of the spokes, the said ends being protected by the metallic ferrules, in which they are arranged, as before described.

35 We prefer in practice to form the felly and spokes of our improved wheel of wood and the remaining parts of metal.

We have entered into a specific and detailed description of the several parts of our 40 improved wheel in order to impart a full, clear, and exact understanding of the same. We do not, however, desire to be understood as confining ourselves to the specific construction of the present embodiment of the invention, as such changes or modifications may be 45 made in practice as fairly fall within the scope of our invention.

Having thus described our invention, what we claim is—

50 1. In a wheel, the combination of a felly, a hub-body having an outwardly-directed sleeve and also having radial spoke-sockets open at their inner ends and an annular recess communicating with the inner ends of the 55 said sockets, spokes interposed between the felly and the hub-body and having their inner ends beveled and arranged in the sockets of the latter, the correspondingly-beveled ferrules arranged on the inner ends of the 60 spokes, the taper sleeve arranged in the annular recess of the body and adjustably connected to said body, and the outer shell surrounding the sleeve of the body and connected to said body, substantially as specified.

65 2. A wheel comprising a felly, a hub-body having a sleeve, spoke-sockets, and an annular recess communicating with the inner ends

of the sockets and also having a peripheral flange forming a continuation of one wall of the spoke-sockets, spokes interposed between the felly and the hub-body and having their inner ends beveled and arranged in the sockets of the latter, the taper sleeve arranged in the annular recess of the body and adjustably connected to said body, a shell arranged on the sleeve of the body and surrounding the taper sleeve and having a peripheral flange surrounding one wall of the spoke-sockets and bearing directly against the spokes, and detachable transverse connections between the flanges of the shell and hub-body and adapted to clamp the same against the spokes, substantially as specified.

3. A wheel comprising a felly, a hub-body having an outwardly-directed sleeve and spoke-sockets and also having a peripheral flange forming a continuation of the inner wall of the spoke-sockets, spokes interposed between the felly and hub-body and arranged in the sockets of the latter, an outer shell arranged on the sleeve of the body and having a peripheral flange surrounding the outer wall of the spoke-sockets and bearing directly against the spokes, and bolts arranged between the spokes and connecting the flanges of the shell and hub-body so as to clamp the same against the spokes, substantially as specified.

4. A wheel comprising a felly, a hub having spoke-receiving sockets open at their inner ends and also having a peripheral flange forming a continuation of the inner side wall of the sockets, spokes interposed between the felly and hub and arranged in the sockets, a spoke-spreader and tightener arranged in the hub in engagement with the inner ends of the spokes, an outer shell having a flange surrounding the outer wall of the spoke-sockets and bearing directly against the spokes, and screws taking through the flange of said shell and the flange of the hub-body between the spokes and serving to connect the shell to the body and clamp the flanges on the spokes, substantially as specified.

5. In a wheel, the combination of a felly, a hub-body having an outwardly-directed sleeve, radial spoke-sockets open at their inner ends, an annular recess communicating with the inner ends of said sockets, and a peripheral flange forming a continuation of the inner side wall of the sockets, spokes interposed between the felly and hub and arranged in the sockets and having their inner ends beveled, correspondingly-beveled ferrules arranged on the inner ends of the spokes, the taper sleeve arranged in the annular recess of the hub-body and adjustably connected to said body, the outer shell surrounding the sleeve of the body and having a flange surrounding the outer wall of the spoke-sockets and bearing directly against the spokes, and screws taking through said flange of the shell and the flange of the hub-body between the spokes and serving to connect the shell to

the body and clamp the flanges on the spokes, substantially as specified.

6. A wheel comprising a hub-body having an outwardly-directed sleeve and also having radial spoke-sockets open at their inner ends and an annular recess communicating with the inner ends of the said sockets, spokes interposed between the felly and the hub-body and having their inner ends beveled, the taper sleeve arranged in the annular recess of the body, connecting-bolts extending through the taper sleeve from the outer end thereof and having threaded inner portions let into screw-tapped sockets in the body, and the outer shell surrounding the outer end of the

taper sleeve and the sleeve of the body and detachably connected to said body, substantially as specified.

In witness whereof we have hereunto set our hands in presence of two subscribing witnesses.
